UNITED STATES PATENT OFFICE

ROLLAND J. ROBISON, OF ROMULUS, OKLAHOMA.

TELEPHONE CUT-OFF.

1,089,673.

Specification of Letters Patent. Patented Mar. 10, 1914

Application filed June 20, 1913. Serial No. 774,894.

To all whom it may concern:

Be it known that I, ROLLAND J. ROBISON, a citizen of the United States, residing at Romulus, in the county of Pottawatomie and State of Oklahoma, have invented certain new and useful Improvements in Telephone Cut-Offs, of which the following is a specification, reference being had to the accompanying drawings.

10 This invention comprehends certain new and useful improvements in telephone cut-offs and has for a special object to provide a device of this character constructed in such manner that several persons may use 15 a rural phone line at the same time.

Another object is to provide an apparatus 20 of this character in which will be employed two line wires attached to each box and to the line wire on the poles at the road, thereby making it possible for any number of 25 conversations to be had over the wire so long as they are not over the same parts.

Another object is to provide an automatic 30 telephone cut-off of this character and connected to the line wire on the poles, as above stated, whereby said line wire becomes single wires from house to house, instead of continuing as one wire along the entire line.

Another object is to provide an automatic 35 telephone cut-off of this character which will be of such construction and operation that the part of the line below the box where a long distance message is being received may be cut off and the line thereby made 40 stronger.

Another object is to provide an automatic 45 phone cut-off which will be of such construction that disturbances (common on rural lines) may be easily detected by cutting off 50 the phone at various places and thereby finding out which party is "butting in" or which wire is grounded.

With the above and other objects in view, my invention consists in certain novel constructions, combinations, and arrangements 55 of parts to be hereinafter more fully described, claimed, and illustrated in the accompanying drawings, in which,

Figure 1 is a front elevational view of my 60 invention applied to a phone box of ordinary construction; and Fig. 2 is a side elevational view thereof. Fig. 3 is a view similar to Fig. 1, showing my invention positioned inside of a phone box; Fig. 4 is a detail sectional view 65 on the line 4-4 of Fig. 3; and Fig. 5 is a similar view on the line 5-5 of Fig. 3.

Referring more specifically to the drawings in which similar reference characters designate corresponding parts throughout the several views, 1 designates the front of 60 a telephone box within which is secured a binding screw 2 upon which are pivoted the curved cut-off levers 3 and 4 having their upper ends covered with insulating material, as shown at 5 and 6 respectively, said levers 65 being crossed near their upper ends, as will be seen by referring to the drawings. The lower ends of the levers 3 and 4 are directed outwardly in opposite directions, as shown at 7 and 8 and normally engaged in the 70 forked upper ends of the pivoted spring members 9 and 10, respectively. The box wire 11 is secured to the screw 2. The screw 2 also has a spring 12 engaged therearound to retain the levers 3 and 4 in raised position, as will be later clearly understood. The 75 spring members 9 and 10 are pivoted upon the binding screws 13 and 14 respectively and have their main portions offset and their lower ends removably engaged beneath the 80 offset portions of the clamp members 15 and 16, said clamp members being secured to the front 1 of the telephone box by means of the screws 17 and 18. To the screws 17 and 18 are connected the inner ends of the auxiliary 85 line wires 19 and 20 respectively, while the wire 21 is connected to the outer ends of said wires 19 and 20. It will therefore be seen that when the message is to be sent in one direction over the main line wire 21 90 by way of the auxiliary line wire 19, the upper insulated end 6 of the lever 4 is swung upwardly, thereby turning said lever 4 upon the screw 2 and disengaging the end 8 thereof from the upper forked end of the spring 95 member 10, thereby breaking the electrical connections between said end 8 of the lever 4 and the spring member 10 and preventing messages from passing over the auxiliary line wire 20. It will be understood that 100 when a message is to be sent in an opposite direction over the main line wire, the lever 3 is operated in a similar manner to disengage the outwardly directed end 7 thereof from the spring member 9 thereby preventing messages from traveling to or from the main line wire 21 by way of the auxiliary line wire 19. It will also be understood that the inner forks of the upper ends of the spring members 9 and 10 are bent 105 outwardly, as clearly shown in the drawings in order that the ends 7 and 8 of the levers 110

3 and 4 may be readily engaged with or disengaged from said spring members 9 and 10.

It will be seen that when the receiver hook 22 is in its lowermost position, it rests upon the levers 3 and 4 and thereby prevents upward movement of either lever. It will therefore be evident that should either of the levers 3 or 4 be in uppermost position 10 during use of the telephone, said lever will be automatically returned to normal position and forced in engagement with the proper spring member upon downward movement of the receiver hook 22 caused by the receiver 15 (not shown) upon replacing of the receiver thereon.

The lower ends of the pivoted spring members 9 and 10 are enlarged and insulated, as shown at 22 and 23, respectively, whereby 20 either of said ends may be engaged and pressed downwardly, thereby disengaging the proper spring member from the clamp member with which it is normally engaged, thereby making it possible to use the members 9 and 10 as temporary cut-offs in calling over one end of the line, as will be 25 readily understood.

In Figs. 3, 4 and 5, I have shown my invention as positioned inside of the telephone box 1 with the receiver hook 22 projecting through its slot in the wall thereof, the same as in Figs. 1 and 2. In this case, however, I have also provided the same wall 30 of the box 1 with two arcuate slots 25 and 26 to either side of the receiver hook slot to accommodate the laterally directed insulated pins 27 and 28 projecting outwardly from the upper insulated ends 5 and 6 of the curved cut-off levers 3 and 4, whereby said 35 levers may be properly operated. In this second form and arrangement of the invention, I have provided the laterally directed insulated pins 29 and 30 upon the lower ends 40 of the pivoted spring members 9 and 10, respectively, and projecting outwardly through suitable openings 31 and 32 in the wall of the box 1, whereby the lower end of 45 either spring member may be pressed inwardly and away from the clamp members 33 and 34 secured upon the inner ends of the screws 17 and 18 and against the inner 50 face of the wall of the box 1.

From the foregoing it will be apparent that I have provided an apparatus by means 55 of which a phone may be automatically cut off or thrown out of operation with the phone or phones to either side thereof or to both sides, when desired.

While I have shown the preferred embodiment of my invention, it will be understood 60 that minor changes in the details of construction may be made within the scope of the appended claims without departing from the spirit of my invention or sacrificing any of the advantages of the same. 65

What I claim is:—

1. A device of the class described comprising a pair of levers, spring members, pivot means for the levers, a wire connected with the pivot means, binding screws, said 70 spring members being electrically connected to the binding screws, auxiliary line wires connected with the binding screws, a main line wire, said auxiliary line wires being connected with the main line wire, said 75 levers being removably connected with the spring members, and pivot means for the spring members.

2. The combination with a telephone box 80 wire and a main line wire, of a binding screw for the box wire, a pair of levers pivoted upon the binding screw, auxiliary line wires connected with the main line wire, binding screws for said auxiliary line wires, clamp members carried by the last mentioned binding 85 screws, spring members engaged with the clamp members, said levers being detachably engaged with the spring members, and means for securing the spring members in position. 90

3. The combination with a telephone box, telephone receiver hook, binding screw, and box wire secured to the binding screw; of a pair of levers pivoted upon the binding screw, a sectional main line wire, auxiliary 95 line wires connected with the sections of the main line wire, binding screws carried by the box for said auxiliary line wires, clamp members carried by the last mentioned binding screws, spring members normally engaged with the clamp members, means for forcing each spring member out of engagement with its clamp member, means for securing the spring members to the telephone box, said levers being held in engagement 100 with the spring members by the receiver hook when in its lower position, and means for disengaging either lever from its spring member when the receiver hook is in raised position. 110

In testimony whereof I hereunto affix my signature in the presence of two witnesses.

ROLLAND J. ROBISON.
